United States Patent Office.

RUDOLPH MARTIN AND MATTHEW HARNER, OF TANEYTOWN, MARYLAND.

Letters Patent No. 104,476, dated June 21, 1870.

IMPROVEMENT IN MACHINE FOR BORING POSTS AND POINTING RAILS.

The Schedule referred to in these Letters Patent and making part of the same.

To all whom it may concern:

Be it known that we, RUDOLPH MARTIN and MATTHEW HARNER, of Taneytown, in the county of Carroll and State of Maryland, have invented a new and improved Machine for Boring Posts and Pointing Rails; and we do hereby declare that the following is a full, clear, and exact description of the same, reference being had to the accompanying drawing making a part of this specification, in which—

Figure 1 is a side elevation, and

Figure 2 is a plan view.

This invention has for its object to bore fence-posts, in order to the making of mortises therein, and to sharpen fence-rails, in order to the insertion of their pointed ends in such mortises.

The invention consists in the combination of a laterally-sliding guide-frame, and the roller and connecting-rods by which it is moved, with a longitudinally-sliding beam, provided with clamps, for holding the post.

It also consists in an arrangement for regulating the height of the clamping device, in which the posts are laid, for the purpose of presenting the middle of the post to the point of the auger.

In the drawing—

A A are two main timbers, projecting laterally from the foundation-frame B.

Upon the timbers is a cross-frame, parallel with the foundation, which frame sustains the stationary auger a, with its gearing, the circular saw b, and the platform c, in which the saw works.

The timbers A also sustain, on the lower sides of those parts projecting beyond the foundation, foot-pieces d d, each pivoted at one end to its timber A, and supported at its other end by hooks e e, which catch over teeth, h h, that project in series from the ends of the timbers A.

Posts i i, pivoted at their lower ends in the foot-pieces d, pass upward through vertical mortises in the timbers A, and sustain upon their upper ends sills k k, parallel with the timbers, and occupying, when the foot-pieces d are sufficiently lowered, recesses cut in the upper sides of the timbers A, for the purpose of receiving them.

C is a guide-frame, resting on the sills i, and arranged to slide upon them.

D is a beam, sliding in grooves lengthwise of the guide-way C by the operation of a pinion in the latter gearing with a rack in the under side of the former; and

l l are holders, fastened to the upper side of the beam D, and provided with set-screws m m, for clamping the posts which the holders receive.

Pins n n are set into the upper part of the beam

D, in pairs at regular intervals, each pair indicating where a hole should be bored in the post.

E is a roller, mounted in bearings at the side of the cross-frame, and connected by rods o o, jointed to knobs set in the roller, with staples in the under side of the guide-frame C.

The roller is furnished with a projecting lever, r, by which it may be rotated, so as to draw along the sills k the guide-frame C, bearing the post clamped in the holders upon the point of the auger a.

After one hole has been bored in the post, the guide-frame is run back by the rotation of the roller in the contrary direction, the beam D slid along in the guide-frame until the next pair of pins n comes opposite the auger, when another hole is bored in a similar manner.

The position of the guide-way and sliding beam with reference to the timbers A may be regulated by raising or lowering the foot-pieces d, so as to always place the middle line of the post opposite the point of the auger.

F is a separate truss-frame, connected with whose upper cross-beam s, by staples, is a platform, t, which slides lengthwise of the cross-beam, and bears a holder, l, furnished with a set-screw, m, which holder is pivoted to the platform, so as to swing entirely around.

The truss-frame F is placed at a convenient distance from the circular saw b, and a fence-rail is clamped in the holder l, so that one end may be sawn across at an angle by the saw. This done, the platform t is slid along the cross-beam until the other side of the rail can be sawn across at a corresponding angle. One end of the rail is then pointed. To point the other end, swing the rail half way around in the holder l, loosen the set-screw m, slide the rail along to the saw, clamp it, and renew the operation.

Having thus described our invention,

What we claim as new, and desire to secure by Letters Patent, is—

1. The combination of the laterally-sliding guide-frame C, roller E, and connecting-rods o, with the longitudinally-sliding beam D, provided with holders l, as set forth.

2. The combination of the timber A, adjustable foot-piece d, post i, sill k, and guide-frame C, in the manner and for the purpose set forth.

To the above specification of our invention, we have signed our hands, this 1st day of March, 1870.

RUDOLPH MARTIN.
MATTHEW HARNER.
